US00D575401S

(12) **United States Design Patent**
Hixson et al.

(10) **Patent No.:** US D575,401 S
(45) **Date of Patent:** ** Aug. 19, 2008

(54) **VESSEL SEALER**

(75) Inventors: **David Hixson**, Longmont, CO (US);
Paul R. Romero, Loveland, CO (US);
Luke Waaler, Longmont, CO (US)

(73) Assignee: **TYCO Healthcare Group LP**, North
Haven, CT (US)

(**) Term: **14 Years**

(21) Appl. No.: **29/288,472**

(22) Filed: **Jun. 12, 2007**

(51) **LOC (8) Cl.** **24-02**

(52) **U.S. Cl.** **D24/144**; D24/146

(58) **Field of Classification Search** D24/133,
D24/143, 145, 146, 147, 144; 606/170, 48,
606/51, 42, 206, 204, 205, 207; 600/564

See application file for complete search history.

(57) **CLAIM**

We claim the ornamental design for a vessel sealer, as shown.

DESCRIPTION

FIG. 1 is a perspective view of a vessel sealer showing our new design;

FIG. 2 is a front view of the vessel sealer;

FIG. 3 is a rear view of the vessel sealer;

FIG. 4 is a top view of the vessel sealer;

FIG. 5 is a bottom view of the vessel sealer;

FIG. 6 is a right side view of the vessel sealer; and,

FIG. 7 is a left side view of the vessel sealer.

1 Claim, 5 Drawing Sheets
